CENTER LOCATING DEVICE

Harold F. Wahl, Portland, Oreg.

Application August 25, 1952, Serial No. 306,220

17 Claims. (Cl. 33—191)

1

This invention relates to a geometrical instrument for mechanically locating the centers of objects having shapes which are either circular or in the form of a regular polygon.

The numerous devices heretofore proposed for this purpose are generally unsatisfactory and are not commonly used in the trades. Most of them require the reading of scales and the making of calibrated adjustments in various joints of a more or less complicated linkage or the like. Such devices, besides being quite susceptible to human and mechanical error, and tedious to use, are intricate and expensive to manufacture, having numerous moving parts and pivotal connections which are subject to looseness and wear. The known devices which are more practical from this standpoint are usually limited as to the shapes and sizes of work pieces they will accommodate.

Objects of the present invention are, therefore, to provide a center locator of general application to a wider range of sizes and shapes; to provide a center locator which is entirely mechanical and automatic in its action and does not rely upon scales and visual measurements; to provide a device which is relatively simple and inexpensive to manufacture, and which is at the same time durable and reliable in operation; to provide a device of few moving parts with a minimum of joints and connections subject to wear and looseness; and, in general, to provide an improved and more practical instrument which will satisfy the needs of the trades better than the known devices.

By the novel application of certain geometrical principles, the present device operates automatically by the simple adjustment of a single movable stop member to contact a surface of the work piece without the necessity for reading scales, taking measurements or making calibrated adjustments. The device in its simplest form will accommodate circular shapes and all regular polygons having a number of sides which is a multiple of four. The principles of the invention are also applicable to other regular polygons, and a form of the device is illustrated which will accommodate a hexagonal shape. The tool may be made in various sizes to find the centers of a wide variety of work pieces such as pistons, wood working stock, bar stock of all the standard shapes and sizes, large cylindrical tank ends, peeler logs to be mounted in a veneer lathe, and for other purposes. The principles of the invention may be applied to both outside and inside caliper and to the location of the centers

2

of geometrical areas on maps, charts, photographs and the like. Obviously, the details of construction will vary in such widely different applications, but the embodiments shown on the accompanying drawings will serve to illustrate the principles of the invention so that others skilled in the art may apply these principles in other fields of use. It is, therefore, to be understood that the accompanying drawings are to be considered merely as illustrative and not limiting the invention.

In the drawings:

Figure 1 is a plan view of a device embodying the principles of the invention for use primarily with objects having a shape which is circular, square or octagonal;

Figure 2 is a sectional view taken on the line 2—2 of Figure 1;

Figure 3 is a sectional view taken on the line 3—3 of Figure 1;

Figure 4 is a sectional view taken on the line 4—4 of Figure 1;

Figure 5 is a fragmentary view of a modification adapted to accommodate hexagonal shapes;

Figure 6 is a diagram illustrating the geometrical principles of the present invention which are involved in locating the center of a circle;

Figure 7 is a diagram illustrating the principles involved in finding the center of a square or octagon; and

Figure 8 is a diagram illustrating the principles involved in finding the center of a hexagon.

Circular and square shapes

Referring first to Figure 6, the rectangular coordinate axes OX and OY form a right angle at the point of intersection O. Circles of different sizes may be drawn tangent to these lines, as shown, having centers at P_1 , P_2 , P_3 . The points of tangency with the line OX are designated at a , b , c , the vertical lines a , a_1 , b , b_1 , c , c_1 being diameters of the respective circles. Horizontal lines a_1 , a_2 , b_1 , b_2 , and c_1 , c_2 are perpendicular to OY and tangent to the respective circles at a_1 , b_1 , c_1 . By geometry, the centers P_1 , P_2 , P_3 fall on a straight line OW, and the points a_1 , b_1 , c_1 fall on a straight line OZ. Also by geometry, a , a_1 equals $2a_1$, a_2 ; b , b_1 equals $2b_1$, b_2 ; and c , c_1 equals $2c_1$, c_2 . Hence, the tangent of the angle A equals $\frac{1}{2}$, making the angle A equal to 26.56505° and the tangent of the angle B equals 2.0, making the angle B equal to 63.43495° . Again, by geometry, the angle XOW equals 45° and its tangent equals 1.0. The angle between OW and OZ is, therefore, 18.43495° .

Thus, the rule may be formulated that the centers P_1, P_2, P_3 lie at the points where perpendiculars dropped from points a_1, b_1, c_1 intersect the 45° line OW , or, more generally stated, perpendiculars dropped from points of intersection of the 63.43495° line OZ with the circles define vertical diameters which are bisected by the 45° line OW to locate the respective centers.

In Fig. 7, the three squares have centers at P_4, P_5 and P_6 lying on the 45° line OW . The points d, e and f are located at the midpoints of the bottom sides of these squares, and the perpendiculars d, d_1, e, e_1, f, f_1 are erected. In this case, the lines d_1, d_2, e_1, e_2 , and f_1, f_2 coincide with the top sides of the squares. Just as in Figure 6, the tangent of the angle A equals $\frac{1}{2}$, giving the same value of 26.56505° for this angle. Again, also, the centers P_4, P_5 , and P_6 lie on points where perpendiculars dropped from the points d_1, e_1, f_1 intersect the 45° line OW .

The foregoing geometrical principles are embodied in a practical mechanical device in Figures 1 and 2. A flat plate 10 having a square corner at O is equipped with a horizontal bottom fence 11 and a vertical side fence 12 to establish the coordinate axes OX and OY in Figures 4 and 5. A 45° stepped guide slot 13 establishes the locus of points on the line OW , and a second guide slot 14 at an angle of 26.56505° from the side fence 12 establishes the locus of points on the line OZ . The extended center lines of both slots intersect at the point O .

When a circular or square shaped object is placed in contact with the fences 11 and 12 , the points a_1, b_1, c_1 , or d_1, e_1, f_1 , are located by a sliding trammel stop 15 mounted for travel in the slot 14 . The work contacting head of trammel stop 15 overlies the plate 10 on opposite sides of the slot 14 and is formed with an angular portion presenting a corner having a blunt knife edge 16 to contact a thick work piece in line contact, as viewed in Figure 2, and in substantially point contact when the third dimension of the work piece is small, as illustrated in Figure 1. The trammel stop 15 also includes a sliding key portion 17 which is elongated in the direction of slot 14 and engages the slot in a good sliding fit to prevent rotation of the trammel stop in the slot.

A trammel bar 20 is secured to the trammel stop 15 in a fixed position so that the trammel bar will be maintained perpendicular to the bottom fence 11 , the parts being held in assembled relation in the slot 14 to provide the desired degree of sliding friction by means of clamp nut 21 . The trammel bar 20 is equipped with a vertical guide slot 24 .

A center locating element in the form of a sliding pilot 25 has a portion 26 engaging and guided by the slot 13 , and another portion 27 engaging and guided by the trammel guide slot 24 . The sliding pilot is preferably equipped with a pilot hole 28 to receive a center drill, center punch or other marking device. The sliding pilot is held in assembled relation with the plate 10 and trammel bar 20 by clamp nuts 29 which act against a sliding bushing 30 to maintain the proper sliding friction. Suitable auxiliary locking devices shown in the art may be employed in conjunction with the clamp nuts 21 and 29 , if desired, to facilitate adjustment without allowing objectionable looseness of the parts. Pilot hole 28 is located at the intersection of the center lines of slots 13 and 24 and contact edge 16 is located at the intersection of the center lines of slots 14 and 24 .

From the foregoing geometrical analysis in con-

nnection with Figure 6, it will be apparent that the slot 14 will guide the trammel stop edge 16 into contact with the top side of a circular work piece at the precise upper end of its vertical diameter corresponding to the points a_1, b_1, c_1 in Figure 6. The cooperating guide means on the center locating element 25 and trammel plate 24 positions the pilot hole 28 on a vertical line beneath the edge 16 , and the pilot guide slot 13 serves to bisect the lines a, a_1, b, b_1, c, c_1 to locate the centers P_1, P_2, P_3 . When a center punch is used to mark the center, the pilot hole 28 prevents drifting of the punch point on the end grain of wood or other irregular surface. The clamping action of trammel stop 15 against the work piece, by the tightening of clamp nuts 21 and 29 when desired, tends to hold the work piece securely, which is of advantage in the case of small work pieces.

In a similar manner, the slot 14 guides the trammel edge 16 down into contact with the precise center of the top edge of a square object, as indicated by the points d_1, e_1, f_1 in Figure 7, and the vertical trammel bar 20 and 45° slot 13 cooperatively guide the center locating element 25 to position the pilot hole 28 to bisect the vertical lines d, d_1, e, e_1, f, f_1 for locating the centers P_4, P_5, P_6 . It is readily apparent that the device of Figure 1 will operate in the same manner to locate the centers of regular polygons having eight, twelve, sixteen or more sides in any number evenly divisible by four.

Hexagonal shape

In Figure 8, a circle of unit radius is drawn about the center P_9 tangent to the line OX at i and tangent to the line OY at j , and the lines OW and OZ drawn as in Figure 4, the point i corresponding to the point c and the point j corresponding to the point c_1 . Circumscribed about this circle is drawn a hexagon, also having its geometrical center at P_9 . The radius P_9i extended intersects the vertex k of the hexagon. The radius P_9l is drawn making a right triangle P_9kl , wherein the angle kP_9l is 30° . Hence, P_9l/P_9k equals cosine 30° equals 0.86602540 , yielding the value of $1.1547+$ for the length of line P_9k , and $0.1547+$ for the length of line jk . Therefore, the tangent of angle C equals

$$\frac{0.1547+}{1}$$

giving the value to the angle C of 8.79397° .

By the well known theorem establishing the proportionality of the corresponding sides of similar triangles, it will be apparent that the corresponding vertices of larger and smaller hexagons will also lie upon the line OV , as illustrated, the entire angle XOV being equal to 98.79397° . In this case, it is convenient to refer all the angles to the OX axis, it being noted that the lines OW , OZ , OY and OV all pass through the point O . Thus, using the OX axis as a reference or base line, the angle XOW equals 45° , the angle XOZ equals 63.43495° , the angle XOY equals 90° , and the angle XOV equals 98.79397° .

Further, considering the OX line as the base or reference line, the tangent of the angle XOW equals 1 , whereas the tangent of the angle XOZ equals 2 , whereby perpendiculars dropped from the points g_1, h_1, i_1 are bisected by the line OW to locate the centers of the respective hexagons at P_7, P_8 , and P_9 . Again, by geometry, it will be apparent that the line OZ passes through the points g_1, h_1 , just as it passes through the point

i., the inscribed circles for the smaller hexagons being omitted to avoid confusion in the diagram. It is further apparent that if circles were inscribed in the small hexagons, the points g_1 and h_1 would correspond to a_1 and b_1 in Figure 6.

Applying the foregoing geometrical development to a practical center locating device, Figure 5 shows a plate 10a having a bottom fence 11 corresponding to the similarly numbered fence in Figure 1. The plate 10a is also equipped with guide slots 13 and 14 disposed at angles of 45° and 63.43495+° relative to fence 11, as described in Figure 1. It is further understood that the plate 10a is equipped with a trammel stop 15, trammel bar 20, and center locating element 25, as shown in Figures 1 and 2. In Figure 5, however, the side fence 12a is pivotally mounted on a pin 40 having its axis located to correspond to the point O in Figures 1 and 8, whereby it defines the point of intersection of the center lines of guide slots 13 and 14 extended. The work engaging surfaces of the fences 11 and 12a also intersect at this point.

The plate 10a is provided with a hole 41 to receive a pin or screw dowel 42 in the upper end 25 of the fence member to secure the fence at an angle of 90° to the bottom fence 11, as indicated in broken lines. In this position of the fence 12a, the device in Figure 5 functions the same as the device in Figure 1 to locate the centers of round, 30 square and octagonal work pieces.

When the fence 12a is shifted to its full line position, the pin 42 may be inserted into a second hole, not shown, to secure the fence at an angle of 98.79397+° from the bottom fence 11 for locating the centers of hexagonal work pieces. The fence 12a may, of course, be mounted permanently in its full line position, if desired.

Thus, the objects of the invention are attained in a relatively simple, inexpensive and rugged device which is easy to manipulate and use with a high degree of accuracy. When constructed as shown in Figures 1 and 5, the device will accommodate work pieces of very small size, while, on the other hand, it will be apparent to persons skilled in the art that the principles of the invention may be embodied in a device of sufficient size to locate the centers of large logs and circular tank ends and the like.

It will also be apparent to persons skilled in the art that the geometrical development illustrated in Figure 8 may be applied and extended to determine the value of the angle of fence 12a in Figure 5 to locate the centers of objects or areas of other shapes, and it is within the scope of the invention to provide additional holes in the plate 10a, or other equivalent securing means, to position the fence 12a at any such predetermined angle.

Having now described my invention and in what manner the same may be used, what I claim as new and desire to protect by Letters Patent is:

1. In a device for locating the centers of circles and regular polygons, means defining a pair of straight reference lines disposed at a predetermined angle to each other, a movable trammel member, guide means for said trammel member extending in a straight line from the point of intersection of said reference lines at an angle to 70 one of said reference lines having a tangent function of 2.0, a movable center locating element, guide means for said center locating element extending in a straight line from said point of intersection at an angle to said one reference line 75

having a tangent function of 1.0, and cooperating guide means on said trammel member and center locating element to position the latter always on a perpendicular line between said trammel member and said one reference line.

2. A device for locating the centers of circular and regular polygonal objects comprising means to contact the perimeter of the object at two points having a central angle spacing of 90° in 10 the case of a circular object, a movable center locating element, guide means for said element extending in a straight line bisecting said 90° central angle, a movable trammel stop to contact the perimeter at a point opposite one of said two points of contact, guide means for said trammel stop extending at an angle of 18.43495+° to said first guide means and directed in a straight line intersecting the point of intersection of tangent lines through said first two points of contact, 20 and cooperating guide means on said trammel stop and center locating element to maintain said trammel stop and center locating element on a line perpendicular to said tangent line through said one point of contact.

3. A device for locating the centers of circular and regular polygonal objects comprising means to contact the perimeter of the object at two points having a central angle spacing of 90° in the case of a circular object, whereby tangent lines of said two points of contact meet at a point of intersection bisecting said 90° central angle, a movable center locating element, guide means for said element extending in a straight line through said point of intersection bisecting said 90° central angle, a movable trammel stop to contact the perimeter at a point opposite one of said tangent lines, guide means for said trammel stop extending in a straight line from said point of intersection at an angle of 63.43495-° to said one tangent line, and cooperating guide means on said trammel stop and center locating element to maintain said trammel stop and center locating element on a line perpendicular to said one tangent line.

4. A center locator for circular and regular polygonal objects comprising a pair of fence members disposed at a predetermined angle to each other to contact the periphery of the object, a center locating element constrained to movement in a straight line at an angle of 45° to one of said fence members, a trammel stop constrained to movement in a straight line at an angle of 63.43495-° to said one fence member to contact the periphery of the object, and means on said trammel stop to position said center locating element always on a perpendicular line from said trammel stop to said one fence.

5. A center locator for objects of circular and regular polygonal shapes comprising a pair of straight fence members disposed at a predetermined angle to each other to contact two points on the periphery of the object having a central angle spacing of 90° in the case of a circular object, a movable trammel stop constrained to travel in a straight line at an angle of 63.43495-° to one of said fence members to contact a third point on the periphery of the object, a movable center locating element constrained to travel in a straight line at an angle of 45° to said one fence member, and cooperating means on said trammel stop and center locating element to position the latter always on a line from said trammel stop extending perpendicular to said one fence.

6. A center locator for objects of circular and regular polygonal shapes comprising a pair of

straight fence members disposed at a predetermined angle to each other to contact the periphery of the object, a movable trammel stop to contact the periphery of the object, said trammel stop having a locus in a straight line extending from the point of intersection of said fence lines at an angle of 63.43495° to one of said fence members, a movable center locating element having a locus in a straight line extending from said point of intersection at an angle of 45° to said one fence member, and cooperating guide means on said trammel stop and center locating element to position the latter always on a perpendicular line between said trammel stop and said one fence member.

7. A center locator for objects of circular and regular polygonal shapes comprising a pair of straight fence members disposed at a predetermined angle to each other to contact the periphery of the object, a movable trammel stop to contact the periphery of the object, guide means for said trammel stop extending in a straight line from the point of intersection of said fence lines at an angle of 63.43495° to one of said fence members, a movable center locating element, guide means for said center locating element extending in a straight line from said point of intersection at an angle of 45° to said one fence member, and cooperating guide means on said trammel stop and center locating element to position the latter always on a perpendicular line between said trammel stop and said one fence member.

8. A center locator for objects of circular shape and regular polygons having a number of sides equal to a multiple of four comprising the structure defined in claim 7 wherein the two fence members are disposed at an angle of 90° to each other.

9. A center locator for objects of hexagonal shape comprising the structure defined in claim 7 wherein the two fence members are disposed at an angle of 98.79397° to each other.

10. A center locator as defined in claim 7 having means to secure the other fence member at different predetermined angles relative to said one fence member.

11. A center locator as defined in claim 7 in which at least one of said fence members is pivotally mounted on the locator, and fastening means to secure said pivotally mounted fence member in at least one other angular relation different from said first predetermined angular relation between said fence members.

12. A center locator for objects of circular and regular polygonal shapes comprising a plate having a pair of straight fence members disposed at a predetermined angle to each other to contact the periphery of the object, a trammel guide slot in said plate extending on a line from the point of intersection of said fence lines at an angle of 63.43495° to one of said fence members, a sliding trammel stop movable in said slot to contact the periphery of the object, a slot in said plate extending in a straight line from said point of intersection at an angle of 45° to said one fence member, a center locating element movable in said last mentioned slot, and cooperating guide means on said trammel stop and center locating element to position the latter always on a perpendicular line between said trammel stop and said one fence.

13. A device for locating the center points of circles and regular polygons comprising means defining a pair of intersecting straight reference

lines disposed at 90 degrees with respect to each other, a movable trammel member, guide means for said trammel member operably effective along a straight line intersecting said reference lines at the point of intersection of such lines with said line extending at an angle with respect to one of said reference lines, said angle having a tangent function of 2.0 , a movable center locating element, guide means for said center locating element extending along a straight line from the point of intersection of said reference lines and at an angle with respect to the aforesaid one reference line, said angle having a tangent function of 1.0 , and cooperative orientation means operatively connecting said trammel member with said center locating element and functioning to maintain said member and element in positions perpendicularly related with respect to said one reference line aforesaid.

20 14. A center locator for circular and regular polygonal objects comprising a base for the perpendicular support of one of said objects, fence members carried by said base and disposed at predetermined angular relation with respect to each other and for peripheral side contact with said perpendicularly supported object, a center locating element mounted upon said base and arranged for straight line travel at an angle of 45 degrees with respect to one of said fence members and into a position adjacent one end of said object, a trammel stop mounted upon said base and arranged for straight line travel at an angle of 63.43495 degrees with respect to said one fence member and for peripheral side contact with said object, and orientation means connecting and maintaining said center locating element and said trammel stop in aligned positions along a line disposed perpendicular with respect to said one fence member.

35 15. A center locator for circular and regular polygonal objects comprising a base for the perpendicular support of one of said objects, fence members carried by said base and disposed at predetermined angular relation with respect to each other and for peripheral side contact with said perpendicularly supported object, a center locating element mounted upon said base and arranged for straight line travel along a path following a line bisecting the angle formed between said fence members and into a position adjacent one end of said object, a trammel stop mounted upon said base and arranged for travel along a straight line radiating from the junction of said fence members and disposed at a predetermined angular relation with respect to said straight line path of said center locating element and for peripheral side contact with said object, and orientation means connecting and maintaining said locating element and said trammel stop in aligned positions upon a line disposed in a given angular relation with respect to one of said fence members.

45 16. A center locator for objects having a circular or regular polygonal end comprising a flat base adapted to contact said end of the object, a pair of fence members carried by said base and disposed in predetermined angular relation with respect to each other for peripheral side contact with said object adjacent said end, a movable center locating element mounted upon said base and constrained to travel in a path along a straight line bisecting the angle formed between said fence members and into a position adjacent said end of the object, a movable trammel stop mounted upon said base and constrained to travel

in a path along a straight line radiating from the juncture of said fence members and disposed in a predetermined angular position with respect to said straight line path of said center locating element and for peripheral side contact with said object adjacent said end, and orientation means connecting and maintaining said locating element and said trammel stop in aligned positions upon a line disposed in a predetermined angular relation with respect to one of said fence members.

17. In a device for locating the centers of circles and regular polygons, a flat base member, means on said base member defining pair of straight reference lines disposed at a predetermined angle to each other, a movable center locating element mounted on said base member

10
5

and constrained to travel in a path along a straight line bisecting the angle formed between said reference lines, a movable trammel stop mounted on said base member and constrained to travel in a path along a straight line radiating from the juncture of said reference lines and disposed in a predetermined angular position with respect to said straight line path of said center locating element, and orientation means engaging said base and connecting and maintaining said locating element and trammel member in aligned positions upon a line disposed in predetermined angular relation to one of said reference lines.
